UNITED STATES PATENT OFFICE.

THOMAS SCHUSTER, OF PHOENIX, ARIZONA.

WATER GATE.

Application filed March 17, 1921. Serial No. 453,136.

To all whom it may concern:

Be it known that I, THOMAS SCHUSTER, a citizen of the United States, residing at Phoenix, in the county of Maricopa and State of Arizona, have invented certain new and useful Improvements in Water Gates; and I do declare the following to be a full, clear, and exact description of the invention, such as will enable others skilled in the art to which it appertains to make and use the same.

This invention relates to improvements in water gates and has particular reference to a device of this kind which is especially designed to be used in connection with irrigating systems, although it can well be used in connection with sewer systems, flumes, and for various other purposes.

The principal object of the invention is to generally improve upon devices of this class by the provision of one of extreme simplicity and durability which can be installed by unskilled hands.

Another object of the invention is to provide a device of this class which is made up of comparatively few and inexpensive parts, one of said parts being in the form or a pre-cast element and including a reinforced centrally-apertured plate, from the rear face of which extends an integral shelf-like anchor adapted to be embedded in the earth to retain the plate in position, said anchor having the additional functions of constituting a rest for a pipe, and a guide for the latter for forcing it into the central opening in said plate.

Other features and advantages of the invention will be apparent during the course of the following description.

In the accompanying drawings forming a part of this specification and in which like numerals are used to designate like parts throughout its length:

Figure 1 is a central vertical sectional view through a gate constructed in accordance with this invention, showing the same in use in an irrigation ditch.

Figure 2 is a front elevational view of the gate.

Figure 3 is a sectional view taken on the plane of the line 3—3 of Figure 4.

Figure 4 is a section taken on the line 4—4 of Figure 3.

Figures 5, 6 and 7 are detailed perspective

views of a slightly modified type of castings employed in the make-up of my gate.

Referring to the drawings by numerals, 1 designates a concrete casting which includes a vertical reinforced plate 2 having a central pipe opening 3, tapered if desired. Extending from the rear face of the plate 2, integral therewith and arranged in a substantial horizontal plane with the lower portion of the pipe opening 3 is a shelf-like anchoring leg 4 which serves, as before indicated, the additional function of a seat for a drain pipe 5 and as means for guiding the latter into the opening 3. To facilitate this guiding and assembling of parts, the upper face of the anchoring leg is formed with a relatively deep guide channel 6. Plate 2 is formed around its margins with a plurality of bolt holes intended to permit passage of retaining bolts 7 therethrough, which bolts in turn serve to hold a pair of vertical guides 8 against the front or outer face of the plate. In addition to these guides the plate is equipped on its front face and near its bottom with a horizontal stop 9 which is likewise held in place by bolts 7. It is obvious that the guides 8 serve to retain between them, a slidible closure 10, which covers the pipe opening 3 until it is desired to drain the ditch or permit passage of water through the pipe. To facilitate opening of the closure 10, it may be equipped with a handle 11.

As before intimated, in the Figures 5 to 7, I have disclosed slightly modified forms of concrete castings. This being the case each form will be referred to separately.

Referring first to Figure 5, it will be seen that the casting 1^a, like the casting 1, embodies a vertically disposed plate 2^a, provided with a central pipe opening 3^a and on its rear face with a horizontal anchoring leg 4^a. The latter is also formed in its upper face with a relatively long guide channel 6^a for the pipe. The difference between this form of casting and the one first described resides in the fact that the portion of material on opposite sides of the pipe guide channel 6^a is gradually thinned as indicated at 12 to render the anchoring leg more rigid. Also, this form of casting is equipped with reinforcing webs 13 at the juncture of the anchoring leg and plate, these webs having the additional function of better anchoring.

the casting in the earth and preventing possible side shifting. Other than this, there are no further differences of construction.

- Referring now to Figure 6, 1^b designates 5 the concrete casting which includes the plate-like part 2^b which is provided with a central pipe opening 3^b. Extending laterally from the rear face of this plate is the anchoring leg 4^b which instead of being relatively wide 10 and thin like the ones already described, is comparatively thick to increase its strength and yet form a very effective anchor. This leg like those already described is formed in its upper face with a relatively long pipe 15 guide channel 6^b.

- To simplify and reduce the cost of manufacture of such castings, I also contemplate using one of the type disclosed in Figure 7, wherein it is designated generally by the 20 numeral 1^c, the same including a plate-like part 2^c, having a central pipe opening 3^c, and being equipped with an integral shelf-like anchoring legs 4^c which instead of having its upper face grooved, has it formed plain. 25 This type of casting is simpler and less expensive than any of those previously described. All of the castings described are equipped with the marginal bolt holes to 30 permit attachment of the guides 8, stop piece 9 and closure 10.

- As before suggested, the gate is especially intended to be used in irrigation ditches. To disclose the manner in which it is positioned in one of such ditches, I have shown, 35 in Figure 1, the position that the gate takes. Referring to this figure, it will be seen that the letter D designates the ditch, at one end of which is a vertical bank B formed with a bore for passage for the drain pipe 5. 40 The plate-like part of the concrete casting is positioned against the bank and the anchoring leg or shelf 4 is embedded in the latter in the manner shown, the pipe 5 being permitted to rest in the guide channel 45 6 with its end extending into the opening 3, concrete or the like being employed to secure the pipe in this opening. I have found that in placing the gate in a ditch, it is well to embed the lower portions of 50 the same in the bottom of the ditch as indicated to prevent, to a certain extent, water from undermining the structure in such a manner as to cause a "washout". Hence, with the gate in the position shown, it will 55 be seen that when it is desired to drain the ditch or permit the passage of water from it to another ditch through the pipe 5, this can be done by simply raising the closure 10 sufficiently high to uncover the open- 60 ing 3.

- The foregoing is one way in which the gate may be used. However, as before stated, it is adaptable for use in sewer systems, flumes and various other water sys- 65 tems.

A careful consideration of the foregoing description taken in connection with the accompanying drawings ought to be sufficient to enable persons skilled in the art to which the invention relates, to obtain a clear understanding of the same. Therefore, a more detailed and lengthy description is deemed unnecessary.

Since probably the best results may be obtained with the construction and arrangement herein shown and described, this construction and arrangement is taken as a preferred embodiment of the invention. However, minor changes within the scope of the subjoined claims may be resorted to.

I claim:—

1. A water gate comprising a pre-cast unit embodying a plate for vertical disposition in the ditch, said plate having a central opening and being equipped with a horizontal shelf-like extention on one side forming a rest for the pipe, a guide for facilitating insertion thereof into the opening, and an anchoring leg for the unit.

2. A water gate comprising a pre-cast concrete member including a vertical plate having marginal bolt-holes, a central pipe opening, and a horizontal shelf-like anchoring leg, the upper face of which is disposed in a plane with the bottom portion of said pipe opening to serve as a rest for the pipe and as a means to guide it into said opening, vertically disposed spaced guides resting against the outer face of the plate, bolts passing thru said guides and thru the aforesaid bolt-holes, a horizontal stop cooperative with the guides, and a closure slidably between the guides and resting on said stop and serving to close said pipe opening.

3. The structure set forth in claim 1, said leg having a relatively deep guide channel in its upper face, which has the additional function of preventing displacement or disconnection of the pipe from the aperture in said plate.

4. A water gate of the type specified comprising a pre-cast concrete unit embodying a plate for vertical disposition in the ditch, said plate being formed with a central opening into which one end of the piping is received, and a shelf-like extension projecting from the rear side of said plate, said extension being substantially the same in width as said plate and having its upper face disposed in a plane with the lower portion of said opening, said extension being formed between its side edges with a groove constituting a seat for the piping, and vertical webs disposed at the juncture of said partition and said plate serving to reinforce said unit and also functioning to prevent side shifting of the unit in the ditch.

5. A water gate of the class described comprising a pre-cast concrete unit embodying

a plate for transverse and vertical disposition in the ditch, said plate being formed at its center with an opening into which one end of the piping is extended, and also being formed with an integral extension projecting from one side of said plate, being disposed in a plane with the lower portion of said opening and being of a greater width

than the diameter of the pipe so that when the unit is in position in the ditch, portions of said extension project on opposite sides of said pipe to insure effective anchoring of the unit in the ditch. ¹⁰

In testimony whereof I have hereunto set my hand.

THOMAS SCHUSTER.
